MECHANISM FOR REGISTERING THE OPERATIONS OF TICKET ISSUING MACHINES

Alfred W. Pride, Berkeley, Calif.

Application March 3, 1937, Serial No. 123,788

15 Claims. (Cl. 235—92)

The present invention relates to improvements in mechanism for registering the operations of ticket issuing machines of the type adapted for use in connection with betting on races or similar contests where the betting "odds" are calculated by the so-called "parimutuel" system.

In Patent Number 2,150,761, issued on March 14, 1939, to Harry C. Craig and Alfred W. Pride, entitled "Ticket printing and issuing machine", there is described a machine for printing and issuing tickets bearing all information necessary to identify a particular race or races and particular entries, in favor of which a bet is made together with means for registering the total number of tickets issued on each entry and totalizing the tickets issued for the entire race.

The said patent discloses a mechanically operated counting device contained by the ticket issuing machine for registering the number of tickets sold on each entry and for registering the total sales for each race. There is also disclosed diagrammatically therein a system comprising electrically actuated mechanical counters for effecting the same registration and totalization at a point remote from the machine. Each of these systems is complete and adequate in its application to a single ticket issuing machine of the kind disclosed. The problem of rapid and accurate registration of ticket sales, however, is rendered complex by reason of the fact that large numbers of machines are necessary to issue tickets in the quantities and at the speed required to accommodate the usual patronage. Further complexing the problem is the fact that it is customary that the machines be arranged in remotely spaced groups making mechanical connection between more than a very limited number of machines impractical.

The registration of all tickets issued for all entries of a race and of the total ticket sales, irrespective of the number of machines issuing tickets, is essential to the practice of the parimutuel system, wherein betting odds are determined by computations based upon this data.

It is the object of the present invention to improve in general the operation of a group of ticket printing and issuing machines and to provide a system for the synchronization of a group of such machines to the end that electrical mechanical counting of the operations of the individual machines may be effected rapidly, through relatively simple mechanism, accurately and without interference between machines in the

same group, even though the operation of more than one machine be instigated simultaneously.

It is a further object of the present invention to provide a system in which the operation of several classes of machines may be recorded separately, without interference and reduce to a minimum the time required for the individual counting operation of any one machine so that as many as possible machines may be accommodated on a single counting circuit.

While the invention is exemplified herein as applied to machines used for printing and issuing tickets, it will appear that the principles thereof are adaptable to the counting and registering of various other kinds of operations, as the ticket printing operation in itself forms no part of the present application.

One form of the invention is exemplified in the accompanying drawings, to which detailed reference is made in the following specification. In the specification further of the objects and advantages of the invention are made apparent.

In the drawings—

Figs. 1 and 2 are a wiring diagram of a system embodying the present invention with certain mechanical elements diagrammatically illustrated therein, the bottom portion of the sheet in Fig. 2 being a continuation of the top portion of the sheet in Fig. 1, and

Fig. 3 is an enlarged wiring diagram of a portion of a system of the kind shown in Figs. 1 and 2 and illustrating the application of a safety switch circuit thereto.

The drawings are diagrammatical and illustrative of the principles upon which the invention may be practised rather than of a complete system, it being understood that the number and classifications of machines in any system are determined by the particular requirements of the course or track where the system is installed. It will appear, as the description proceeds, that the invention is readily adapted to the varying conditions and requirements of different courses.

As a premise to the description of the invention as it is illustrated in the drawings, let it be assumed that there are, as usual, three general classes of bets which may be made in favor of any entry of any race. These classes are known as "win," "place" and "show." To "win," an entry must finish first; while to "place," the entry must finish first or second; and to "show," the entry may finish either first, second or third.

Inasmuch as the odds payable in any of these three classifications are based upon the amount of money placed upon all entries under that par-

ticular classification, it is apparent that three entirely separate systems must be operated to produce three separate results. The present invention contemplates the use of three substantially identical systems for this purpose, which systems may be to some extent mechanically co-ordinated, but which must be maintained separate and independent with respect to impulses in the electrical circuits which control the counting and totalizing. As the three systems are identical in principles of operation, only one will be described in detail, the description of the others being sufficient only to illustrate the manner in which the three may be correlated.

15 Referring now to the drawings and particularly to Figs. 1 and 2, there are illustrated two typical groups of ticket-issuing machines. Each of these groups is driven from a separate drive shaft, said shafts being indicated at 20 and 21, 20 and the machines of each group are divided into classifications of "win," "place" and "show." The "win" machines are indicated by the reference numeral 22, the "place" machines by the numeral 23 and the "show" machines by the numeral 24. 25 While there are but three "win" machines in each group and one each of the "place" and "show" machines, it is to be understood that the drawings are simply illustrative of the principle and that the number of machines in each classification and in each group may be greatly varied.

The construction of the individual machines is described in detail in the patent above referred to. For the purpose of the present description it will suffice to say that each machine includes a multi-point circuit selector, which, upon adjustment of the machine to print and issue a ticket for any particular entry, is actuated to select a counter circuit corresponding to that entry. Such circuit selectors are illustrated diagrammatically at 25 in Figs. 1 and 2 and should be of a non-bridging type, one suitable form of which is disclosed in the said patent. Electrical energy from a common source, such as a battery 26 (see Fig. 2), is carried by a conductor 27 to banks of electromechanically actuated counters 28. Each bank of counters 28 comprises ten counters numbered from "1" to "10" to be actuated selectively upon the sale of tickets on correspondingly numbered entries and a total counter marked "T" to be actuated upon the sale of a ticket upon any entry.

A variable resistance 29 in the total counter circuit and a similar resistance 30 in the circuit of the numbered entry counters permit balancing of the electrical constants of the circuits for most efficient operation of the electromagnets which actuate the counters. Each of the counters, "1" to "10" inclusive, is connected by a separate conductor, as illustrated, with the respective contact points of the circuit selector 25. A sliding finger 31, engageable selectively with the contact points of the selector 25, is connected with a switch 32 comprising a pivoted arm 33 which may close to complete a circuit through a conductor 12 to the battery 26.

A conductor 11 connects the totalizing counter "T" with a switch 34, which also includes the pivoted arm 33. Closing of the switch 34 by the arm 33 completes the circuit to the battery 26 through the common conductor 12. Condensers 35 and 36 are placed in parallel with the switches 32 and 34 to reduce arcing at the contact points of these switches. The switches 32 and 34 are closed by any suitable mechanical means, as, for example, a rotatable cam 37 which is designed

and driven by the ticket-issuing mechanism to effect closing of the points to close the entry counting and totalizing circuits at an instant predetermined with relation to the cyclic operation of the machine. 5

As an alternative to the structure just described, the switches 32 and 34 which control respectively the circuit to the entry counters and the circuit to the "total" counter may be disposed at different positions with respect to the cam. For example, as illustrated in the machines on drive shaft 21, the breaker points are disposed 180° apart so that at a given cam speed of 100 R. P. M., the entry counter circuit will be energized .3 second in advance of the "total" counter circuit. This structure necessitates obvious modifications of the timing schedule but for the purpose of simplicity, the timing of the impulses over the counter circuits will be considered as though they were initiated by the device previously described and illustrated in the machines driven from shaft 20.

In order to avoid any possibility of two machines in the same class sending simultaneous or overlapping impulses over their common counter circuit and to ensure against simultaneous operation of any machines on the same drive shaft, which operation might impose a momentary overload on such shaft, the machines are synchronized for successive operation with relation to the rotation of the drive shaft in the manner best illustrated in Figs. 1 and 2. In Figs. 1 and 2, two drive shafts 20 and 21 are illustrated as driving groups of machines 22, 23 and 24 of the "win," "place" and "show" classes respectively. 35 These drive shafts may be continuously rotated by any suitable drive means capable of causing their synchronous operation at approximately constant speed. A driving connection is formed between the drive shafts and each machine, preferably in the form of a chain 38, to ensure the maintaining of predetermined phase positions of the driving clutch members of the ticket-issuing machines. 40

For convenience in timing the points of engagement of the clutch members and the impulse initiating contacts of the switches 32 and 34 in the totalizing counter circuits, it is preferred that the driving connections be of one to one ratio. With this ratio one revolution of the drive shaft results in one revolution of the driving clutch members and one complete cycle of the printing mechanism of the machine after engagement of the driving and driven members of the clutch. This ensures the maintaining of 55 the contact timing cams of the machines in predetermined phase positions.

While any suitable type of drive connection may be used in place of the chains 38, chains are preferred for convenience in mechanical installation and operation. By using driving and driven sprockets with an even number of teeth on each and with the sprockets' center distances established at an integral number of chain pitches the effect of chordal pitch on chain drive 60 operation is of minor importance and the driving clutch members maintain substantially their proper phase relation with respect to the main drive shaft throughout all parts of the revolution of the shaft. 65

In order that the relative time of engagement of the clutches of individual machines may be conveniently adjusted for proper sequence of operation for the distribution of the mechanical load on the main drive shaft throughout its revo- 70

lution and in order that the time contacts may be properly adjusted to initiate impulses over the electric counter circuits which will not overlap or interfere with impulses from other machines, a 5 protractor 38 is mounted on the drive shaft and cooperates with a stationary pointer 40 visibly to indicate the phase position of the drive shaft.

Assuming that there are but three machines of each of the "win," "place" and "show" classes 10 on one drive shaft, thus making nine machines in all driven by said shaft, the point of clutch engagement of these machines could be so adjusted that each machine will be actuated at 40°, as determined by the protractor on the shaft, 15 from the point where the next successive machine is actuated. Depression of the operating handle of any one of these machines will, therefore, result in the same relative point of engagement of its clutch to the main drive shaft, irrespective of the exact position of the drive shaft when the operating handle of the machine is depressed. Thus, should it occur that all of the 20 nine machines on one drive shaft were actuated simultaneously to print and issue a ticket they would operate successively at equally spaced 25 intervals throughout a single complete rotation of the shaft, thus avoiding the tendency to impose an overload upon the shaft which might otherwise occur in the event of simultaneous 30 actuation of more than one machine.

The clutches which control the operation of the individual machines from the drive shafts are preferably, as described in the patent above referred to, of the single cycle, single dog type 35 which releases itself automatically after a complete rotation. It should be understood, however, that the invention is not limited to any particular type of clutch but that various kinds of clutches may be used instead of the one described. 40 For example, clutches engageable at two or more points in one revolution of the driving member may be used to reduce the time lapse following initiation of the ticket-issuing operation by depression of the lever which conditions the clutch 45 for engagement. This of course calls for a rearrangement of the timing of the machines in the system relative to the drive shaft, and as there must be an electric impulse channel to the counters allotted to each machine for each point 50 of possible clutch engagement, the number of machines that can be operated with a given counter is reduced by the more rapidly operating type of clutch under the present system.

As previously stated, the two drive shafts 28 55 and 21 and as many other similar drive shafts as may be used in the system, are driven at the same rate of speed and synchronously. As each drive shaft is provided with a protractor 38 to indicate its phase position and as the several machines on each shaft are timed through their clutches to operate at equally spaced intervals throughout a complete rotation of the shaft, it is simply necessary to regulate the phase positions 60 of the shafts to insure against simultaneous operation of two or more machines on different shafts.

The principal reason for employing more than a single drive shaft is that, for convenience in issuing tickets, the machines are often placed in 65 groups at different locations in the vicinity of the racing track. The spacing of these groups of machines is too remote to permit practical direct mechanical driving connections between the shafts.

70 For the purpose of maintaining the main drive

shafts 28 and 21 in the same relative position under all conditions as if they were mechanically tied together through gears and would therefore rotate in the same relative positions irrespective of conditions, any known system of synchronous 5 motors may be used, and any means for establishing the relative positions of the shafts either at rest or in motion may be used.

Because of the advantage of pre-setting the impulse initiating contacts in proper operating 10 sequence, phase and duration under static or extremely slow rotational conditions of the drive shaft, the preferred method of driving the shafts synchronously for the purpose of my invention is that illustrated in Fig. 1 of the drawings where 15 a system of motors known as the "Selsyn" or "Synchro-tie" system is shown. A detailed discussion of the theory of these systems is unnecessary in the present description as the system itself is well known as a medium to transmit motion electrically between two or more points 20 which cannot conveniently be interconnected mechanically.

Briefly, the system may be considered as two 25 or more identical three-phase wound rotor induction motors. The stator windings are excited from a common power source, and the rotors electrically interconnected. One motor, the "transmitter," is located at the point where the motion 30 is generated. The other motors, the "receivers," are located at the points where the motion 35 is to be duplicated. Under these conditions, for each pair of poles, there is only one relative position of the rotors where the secondary voltages will be exactly opposed so that no current will circulate in the secondary windings. For other positions a current will circulate in the 40 rotor windings and torque will result, tending to turn the rotors to that position where the voltages are again equal and opposite. If, therefore, one rotor is turned, the other rotors will tend to assume exactly the same position.

Referring again to Fig. 1 of the drawings, there is shown a receiver motor 45 for driving each of the shafts 28 and 21. The stators of these motors 45 are connected with a common three-phase circuit 46, which circuit also excites the stator of a transmitter or generator motor 47 and supplies energy to a synchronous driving motor 48. A shaft 49 connects the driving motor with the 50 rotor of the generator 47 and this rotor is electrically connected with the rotors of the receiver motors 45 by means of a three-phase circuit 50. The motor 48, therefore, drives the generator 47 which, in turn, actuates through induction 55 the receiver motors 45 to rotate the shafts 28 and 21. As rotation of either one of the shafts 28 or 21 will rotate its associated motor 45 and, through induction, the other motors 45 and the generator 47, the shafts are for practical purposes 60 as effectively connected as though they were mechanically geared to each other.

Reduction gearing indicated at 51 is interposed between each of the shafts and its motor 45 to cause the shaft to rotate at a speed practical for the operation of ticket-issuing machinery. Similar reduction gearing, indicated at 52, may be interposed between the shaft of motor 48 and a countershaft 53 which may carry a master protractor, as shown at 54.

70 Assuming that the single cycle clutch engaging at predetermined phase position is used in the system and that there are four drive shafts like those shown at 28 and 21, each driving three machines of the "win" classification, the twelve 75

"win" machines must all register upon the counters of the "win" totalizer and the timing of these machines would be as follows:

Determining the position of the drive shafts from their respective protractors which will be set for identical readings, with the synchronous motors energized and so locked in proper phase position, the first "win" machine will be adjusted to initiate an impulse over the counter circuit at 30° drive shaft protractor reading, the second at 60°, the third at 90°, and so on, the twelve machines being equally separated as to impulse timing throughout a full revolution of the drive shaft. The positions of clutch engagement of these machines need not coincide with the timing of the electric impulses, as the timing contacts which control the impulses to the totalizers may be adjusted to accurate phase position, independently of the position of clutch engagement.

As there need be no particular coordination between the mechanical starting times of the machines and the times at which the electric impulses are initiated, it is conceivable that the timing may in some instances be such for a particular machine that its electric contacts are closed while the clutch is in its position of rest, thus causing the counter-circuit controlled by this machine to remain closed for an extended period of time. This may be avoided by varying the phase timing of clutch engagement of that machine a few degrees from its regular position.

The number of machines in circuit with a single totalizer is limited by reason of the fact that some time is required for the operation of the mechanical counting devices used in the totalizers. If the drive shafts are rotating at a uniform speed of 100 R. P. M., a single revolution occupies .6 second, while one-twelfth of this time or .05 second is required for 30 degrees of each revolution which is the time allotted to each of the twelve machines.

Assuming that the breaker points 34, which complete the circuit to the totalizer, are closed for 14 degrees of the cycle and open for 16 degrees of the cycle, this allows approximately .0233 second's time to advance the electromagnetically actuated counter one step and .0267 second's time for the counter to return to a position preparatory to being advanced by the next subsequent impulse. Thus a total time of .05 second, which is equal to the time occupied by rotation of the drive shaft through 30 degrees is allowed for the operation of the counters. It may be stated that this and even greater speeds may reasonably be expected from certain commercially available types of counters.

It is possible, however, that the timing just described may be difficult to effect because of non-uniform speed of the timing cams 37 which might result from such causes as back lash in the driving chains or by variations in load. If such non-uniform speed reduced the period that the contacts were closed to .020 second's time or about 12 degrees of drive shaft rotation the interval of current flow through the counter might be insufficient to effect its operation and that impulse would not be registered. On the other hand, if the intervening period of open contacts were reduced to .0233 second's time or 14 degrees of drive shaft operation, one machine might send its impulse over a circuit and to a counter just energized by a previously operated machine before the counter had returned

to normal position and the counter would fail to be advanced.

To avoid this possibility of error, due to non-uniformity of drive shaft speed, or other factors effecting contact timing, an accurate timing contact device may be driven by the main shaft 49 or countershaft 53 of which the speeds are constant, and interposed in the battery circuit which supplies energy to the counters. Such a device is illustrated in Fig. 1 and comprises a 10 pair of breaker points 60 bridged by a condenser 61 and connected in the battery circuit by a conductor 62 leading directly to the battery 26a (shown as an alternative to the battery 26 to illustrate this circuit), and a conductor 63 leading to the wires 12 which return to the battery through the circuit selectors and counters. A twelve-point cam 65 fixed to the counter-shaft 53 for rotation therewith is designed to effect opening and closing of the breaker points at 20 more accurately timed intervals. With the twelve-machine system described above, the cam will close the circuit for 14° and open the circuit for 16°, alternately. The timing of the machines in the system will then be varied. For example, the closed contact time of the machines may be increased from 14° to 20°. The first machine would then operate to close the circuit from about 357° or -3° to 17° drive shaft position. With the accurate timing contact closing the same circuit from 0° to 14°, there is a 3° tolerance for error at either the opening or closing period, which is more than sufficient to overcome any possible error due to non-uniformity in drive shaft or switch operating cam 35 speeds. In the drawings, this accurate timing feature is illustrated only in connection with the "show" totalizer and a separate battery circuit is used. It is to be understood that this feature may be used on any or all of the "win," "place" 40 and "show" totalizers, and that a single battery may be used to supply energy to all of the totalizers.

Because the machines and the bearings of the main drive shaft, as well as other parts of the system, are subject to accidents which might place an excessive load on the motor driving the shaft and because that motor might be pulled out of synchronism with the generator and other motors, resulting in disturbance to the timing 50 of electric impulses from machines driven thereby, it is desirable to have some means for automatically disconnecting the motor under these conditions. It is likewise desirable to disconnect the totalizer circuits associated with the machines driven by the disabled main drive shaft and also to render the individual machines driven by the shaft inoperative.

A preferred structure for means for disabling one of the drive shafts, together with the machines driven by it and the circuits to totalizers connected with said machines, is illustrated in Fig. 3 of the drawings. Fig. 3 illustrates a somewhat abbreviated system employing but three ticket-issuing machines, one for the "win" totalizer, one for the "place" totalizer, and one for the "show" totalizer, the "win" totalizer only being illustrated in this figure. It will be obvious, however, from the following description of the system illustrated in Fig. 3, that the principles 70 thereof are readily adaptable to the more extended system illustrated in Figs. 1 and 2.

In the A. C. rotor circuit of the motor 45 which drives the main drive shaft 20 in Fig. 3, there is included a current-sensitive relay switch 70 75

in one-phase wire, the current responsive operation of which is adjustable. This relay may be set to be operated by a current of approximately two-thirds of the pull-out current of the synchronous motor 45. Assuming that the current in the lead, which includes the switch 78 under motor operation, has a normal rating of one ampere, and that the pull-out current of the motor is five amperes, the relay 78 is set to 10 operate and close its switch 71 at 3.5 amperes. A trip coil 72 is included in the same circuit as the switch 71, to be energized by closing of the switch 71. The trip coil 72 operates a multiple switch comprising a plurality of pivoted levers 15 73, all connected with an armature 74 which is moved upwardly upon energization of the trip coil 72. The three uppermost pivoted contact levers 73 of the multiple switch control the rotor circuit of the motor 45 so that upon the event 20 of a current of 3.5 amperes flowing through the coil of the relay 78, the relay switch 71 will be closed to energize the trip coil 72 and to open the motor circuit, thereby causing the main drive shaft 20 to come to rest promptly upon the 25 imposition of an over-load on the motor 45.

The three lowermost pivoted contact arms 73 of the multiple switch control the "win," the "place" and the "show" totalizer units through 30 switch circuits which include the wires 75, 76 and 77, respectively, leading to the wires 12 of these circuits, and the wires 78, 79 and 80, respectively, leading from these circuits. Consequently, upon energization of the trip coil 72, which occurs upon over-loading of the motor 45, the circuits to the totalizers are broken and no impulses may be initiated by the machines driven by the shaft 20 to affect these totalizers as long as the motor is disabled and the multiple switch is open. This is desirable because should 40 the over-load conditions cause the main drive shaft to come to rest suddenly with one of the totalizer timer contacts closed, the operation of the totalizing system would be disturbed.

The multiple switch may also control a lock-out 45 circuit of the machines in the group driven by the disabled drive shaft. In the above referred to Patent Number 2,150,761 there is described a relay-actuated lock operable from a remote point to prevent operation of any of the machines at 50 any but the proper time and which is intended to be controlled by an official by means of a switch included in the circuit which energizes the relays. Such relays are diagrammatically indicated at 55 in Fig. 3, and the circuit which supplies them with energy includes the wires 86 and 87, the latter of which is controlled by one of the pivoted contact arms of the multiple switch so that upon failure of any part of the mechanism which requires disabling of the drive shaft by cutting out 60 the motor 45, the operating handles of the machines will be automatically locked against operation.

With the use of this multiple switch which is 65 actuated upon over-loading of the synchronous motor 45, the lock-out relays of all of the machines, not having their operating levers in a depressed position upon opening of the motor switch, would render these machines immediately 70 inoperative. The totalizing circuits connected to these machines would be opened so that the timing contacts of any machine in operation at the instant that the motor was cut out might come to rest in their closed position without 75 affecting the operation of the rest of the system.

Thus the errors of totalizing resulting from such a failure of a group of machines would be reduced to a minimum.

The above description stresses the driving of groups of machines from a common shaft by 5 one motor. This may be economical under certain circumstances. However, the system may be applied to individual synchronous motors for each printing-issuing machine.

The present invention is also capable of use 10 to register the sales of so-called "across-the-board" or "combination" tickets. A combination ticket is one which represents a bet equally divided on an entry to win, place or show. For example, a \$6.00 combination ticket on an entry 15 is equivalent to a \$2.00 bet to win, a \$2.00 bet to place, and a \$2.00 bet to show. To provide an accurate total of sales on an entry to win, to place and to show, it would be necessary to 20 record separately the sale of combination tickets on the entry, then divide the total combination sales by three, and add the resulting one-third to each of the win, place and show totals.

To avoid the necessity of such calculations and the loss of time incident to taking several 25 readings for each entry, and performing the necessary calculations, the sale of combination tickets may be recorded directly upon the counters which register straight bets.

This may be accomplished by mechanical connection between the operating levers of three machines so that they will be actuated simultaneously by depression of the operating lever of one of them, which will be termed the control-machine. In this event, three machines are 30 connected, one with each of the win, place, and show 35 totalizers, by means of their circuit selectors 25, in the usual manner.

In order, then, to issue and register the sale of a combination ticket, three selectors are set 40 to the entry upon which the ticket is to issue. The operating lever of the control-machine is then actuated to print a ticket and all three machines operate, with due regard to timing, to initiate impulses to the win, place and show counters for the selected entry. The value registered 45 on each counter will be one-third the face value of the combination ticket.

Although the above description of the operation 50 of the totalizing system is directed to the operation of electrical magnet counters by its initiation of electrical impulses, this invention is not limited to the use of such counters. The impulses initiated by presses when so set up might be employed to perform functions other than those 55 specifically described herein.

Other modifications than those herein illustrated and described may be practiced within the scope of the invention as it is defined in the appended claims.

Having thus described my invention, what I 60 claim and desire to secure by Letters Patent is—

1. Mechanism for registering the operations of a group of independently operable machines, which comprises means including a clutch for 65 connecting each machine to a common continuously operating source of power, means for setting said clutches for engagement only in successively spaced phase positions relative to the source of power, and means operated by each machine 70 to actuate a counting mechanism common to all machines at times definitely related to the time of clutch engagement.

2. Mechanism for registering the operations of a group of independently operable machines, 75

which comprises a drive shaft common to all machines in the group, clutch means effective to initiate operation of the individual machines at predetermined successive phase positions of the drive shaft, a counting mechanism common to all machines in the group, means operable by each machine to send an electrical impulse to the counting mechanism, and means for timing the sending of such impulses with relation to the position of clutch engagement of the machine sending the impulse.

3. In a system for registering the operations of a group of independently operable machines, drive means common to all machines in the group, clutch means effective to initiate operation of the individual machines only at predetermined successive phase positions of the drive means, a counting mechanism common to all machines in the group, and an electric circuit including said counting mechanism and affected upon operation of any of said machines to cause actuation of the counting mechanism.

4. In a system for registering the operations of a plurality of machines, an electrically actuated counting mechanism common to all of the machines, an impulse switch for each machine in circuit with the counting mechanism and timed to send an impulse thereto at a definite phase position in each operation of the machine, a drive shaft common to all said machines, and means for timing the operation of the machines at successive phase positions of the shaft.

5. In a system for registering the operations of a plurality of machines, an electrically actuated counting mechanism common to all the machines, means for initiating electric impulses to the counting mechanism at predetermined successive time intervals, means effective upon operation of any machine to close a circuit to the counting mechanism whereby one of said impulses will effect operation thereof, and means for confining the operation of the individual machines to time periods correlated with said time intervals whereby no two machines will close said circuit in the same time interval.

6. In a system for registering the operations of a plurality of machines, an electrically actuated counting mechanism common to all machines, means for energizing a circuit to the counting mechanism in a cyclic succession of spaced impulses, and switch means controlled by each machine normally to prevent actuation of the counting mechanism by said impulses and operable in timed relation to said impulses upon operation of the machine to permit actuation of the counting mechanism by a selected one of said spaced impulses.

7. In a system for registering the operation of a plurality of machines, an electrically actuated counting mechanism common to all of the machines, an impulse switch in each machine in circuit with the counting mechanism and timed to send an impulse thereto at a definite phase position in each operation of the machine, synchronously operating motors driving said machines to maintain them in synchronized phase positions, and means for timing the operation of the machines to permit closing of their respective impulse switches only at successive phase positions.

8. In a system for registering the operations of a plurality of machines arranged in groups, each machine including means for sending an impulse to an electric counter at a definite time in its cycle of operation, a drive shaft for each group

of machines, a main generator motor, a receiver motor driving each shaft and synchronized with said generator motor, and means for initiating operation of the individual machines only at successively spaced phase positions of the generator motor.

9. In a system for totalizing the operation of a plurality of independently operable machines, an electrically actuated counter common to all the machines, a switch in each machine adapted to close a circuit to and actuate said counter upon operation of a machine, synchronized drive means for all the machines, and means for adjusting the machines to restrict the initiation of operation of each machine to a separate time channel in the cycle of the drive means.

10. In a system for totalizing the operation of a plurality of independently operable machines, an electrically actuated counter common to all the machines, a switch in each machine adapted to close a circuit to and actuate said counter upon operation of a machine, synchronized drive means for all the machines, and means for adjusting the machines for operation successively only, whereby the closing of said switches will take place in definite time channels relative to the cycle of the drive means.

11. In a system for totalizing the operation of a plurality of independently operable machines, an electrically actuated counter common to all the machines, a switch for each machine adapted to close a circuit to and actuate said counter upon operation of a machine, synchronized drive means for all the machines, means for adjusting the machines for operation successively only, whereby the closing of said switches will take place in definite time channels relative to the cycle of the drive means, and a continuously operating switch driven by the drive means to make and break the circuit alternately and timed to prevent overlapping of the said time channels.

12. In a system for totalizing the operations of a plurality of individually operating machines, an electrically actuated counting mechanism, a switch in each machine in circuit with the counting mechanism, means for synchronizing the operation of the machines to close the switches thereof only in separate time channels, and a separate switch in said circuit closing intermittently and once in each time channel to complete the circuit and actuate the counter where one of the first named switches has been closed.

13. In a totalizing system comprising a plurality of independently operable machines driven in groups by drive shafts operated by synchronous motors and an electrically actuated counting mechanism common to all said machines, a cut-out switch for each motor, a cut-out switch in the circuit between each machine and the counting mechanism, and means acting automatically upon the imposition of an overload on a motor to open the motor cut-out switch and the counting mechanism cut-out switch of all machines operated by the shaft driven by said motor.

14. In a totalizing system comprising a plurality of independently operable machines driven in groups by drive shafts operated by synchronous motors and an electrically actuated counting mechanism common to all said machines, a cut-out switch for each motor, a cut-out switch in the circuit between each machine and the counting mechanism, a relay actuated lock-out device in each machine having a switch for closing a circuit thereto and means acting automatically upon the imposition of an overload on a motor

to open the motor cut-out switch, and the counting mechanism cut-out switches and lock-out switches of all machines operated by the shaft driven by said motor.

- 5 15. In a totalizing system comprising a plurality of machines driven by separate synchronously driven shafts, each shaft driving several machines, and electrically actuated totalizers connected with said machines in groups, said groups comprising machines on more than one shaft,

means for synchronizing the operation of all machines connected with any one totalizer, and means effective upon one or more of said machines being disturbed from its synchronous position for causing said shaft to stop, for preventing operation of the machines thereon, and for disconnecting the machines on said shaft from their totalizers.

ALFRED W. PRIDE. 10
